(57) **CLAIM**

The ornamental design for a J-channel siding device, as shown and described.

DESCRIPTION

FIG. 1 is a perspective view of an embodiment of the j-channel siding device.

FIG. 2 is a left side elevation view thereof.

FIG. 3 is a right side elevation view thereof.

FIG. 4 is a rear elevation view thereof.

FIG. 5 is a front elevation view thereof.

FIG. 6 is a top plan view thereof; and,

FIG. 7 is a bottom plan view thereof.

The dash-dot-dash broken lines shown in the Figures define a boundary to which the claim extends but does not include.

1 Claim, 5 Drawing Sheets
